UNITED STATES PATENT OFFICE

120,553

DESIGN FOR A LAMP BASE

James Kernes, Chicago, Ill.

Application December 7, 1939, Serial No. 88,746

Term of patent 3½ years

To all whom it may concern:

Be it known that I, James Kernes, a citizen of the United States, residing at Chicago, in the county of Cook and State of Illinois, have invented a new, original, and ornamental Design for Lamp Base, of which the following is a specification, reference being had to the accompanying drawings, forming part thereof.

Fig. 1 is a perspective view of a lamp base showing my new design.

Fig. 2 is a top plan view of my lamp base with half of said base being shown in dotted lines, it being understood that the portion represented in dotted lines corresponds exactly with portion shown in solid lines.

Fig. 3 is a side elevational view of my lamp base showing my design.

I claim:

The ornamental design for a lamp base, as shown and described.

JAMES KERNES.
